UNITED STATES PATENT OFFICE.

ROBERT H. MULLEN, OF CINCINNATI, OHIO.

SMOKE-CONSUMER.

SPECIFICATION forming part of Letters Patent No. 550,285, dated November 26, 1895.

Application filed May 27, 1895. Serial No. 550,744. (No model.)

To all whom it may concern:

Be it known that I, ROBERT H. MULLEN, a citizen of the United States, residing at Cincinnati, in the county of Hamilton and State 5 of Ohio, have invented certain new and useful Improvements in Smoke-Consumers; and I do hereby declare the following to be a full, clear, and exact description of the invention, reference being had to the annexed drawings, which 10 form part of this specification.

This invention relates to those boiler attachments which automatically admit jets of steam into the furnace or fire-box the instant a door of the same is opened; and my improvement 15 comprises a novel combination of devices for letting the steam on and gradually shutting it off, the details of said devices being hereinafter more fully described.

In the annexed drawings, Figure 1 is a front 20 elevation of a boiler provided with my attachments, the central portions of a pair of gravitating flaps being broken away to expose the air-inlets of the furnace-doors. Fig. 2 is an enlarged axial section of a cataract-gear constituting part of said attachment. Fig. 3 is an 25 enlarged horizontal section through one of the furnace-doors and its accessories. Fig. 4 is an enlarged horizontal section through the front plate of a boiler-setting, which section 30 is taken in the plane of a pair of steam-nozzles.

A represents the front plate of a steam-boiler setting. B B' are the ash-pit doors thereof, and C C' the furnace-doors, the latter being provided with air-inlets c c', normally closed by gravitating flaps D D', hinged to said doors C C' in the manner shown. Projecting from the free edges of these flaps are lugs d d', to which are attached 40 the lower ends of wire-ropes or chains e e', which flexible connections are carried up in front of a pair of grooved disks E E' and then secured to the latter. These disks are keyed to a horizontal rock-shaft F, journaled in 45 bearings f f', projecting from the front A, one end of said shaft being provided with a bevel-wheel G, that gears with a similar wheel H at the top of a short vertical shaft h. Shaft h is journaled in suitable bearings and has fastened to it a horizontally-swinging arm I, whose free end carries a roller i, that is at all 50 times in contact with the furnace-door C'.

Keyed to the opposite end of rock-shaft F is a double-grooved disk J, to which is attached one end of a wire rope or chain K. This chain 55 is wound around one groove, then carried down behind said disk, and has fastened to it a weight k, capable of counterbalancing the various operative parts of the attachment. The other groove of said disk has another 60 flexible connection L fastened to it, which device L is carried up behind said disk, then passed over a grooved roller M, and finally secured to the rod N of a heavy piston O, that traverses a cylinder P, having an air-inlet 65 valve p at bottom and a valveless opening p' at top, as more clearly seen in Fig. 2. Piston O has a minute air-passage closed by an upwardly-opening valve o. The shaft m of roller M carries, also, a cam or eccentric m', adapted 70 at the proper moment to operate against the free end of a lever R, which latter is pivoted to a suitable support at r. Furthermore, this lever has an adjusting-screw r' tapped in it, which screw bears against the end of the stem 75 s of a valve S, the valve being kept normally closed, or almost so, by a spring s', which latter may be external, as seen in Fig. 1, or it may be fitted within said shell, as indicated with dotted lines in Fig. 2.

Valve S is applied to a steam-pipe T, having a throttle-valve t and a series of nozzles U in a horizontal branch T' of said pipe. These nozzles are usually carried horizontally 85 through the front plate A, so as to discharge jets of steam into the furnace and directly under the boiler.

If in fitting up this boiler attachment it should be found that the draft of the furnace is quite sluggish, the screw r' can be so adjusted as to prevent a complete closure of the valve S, in order that a limited quantity of steam may constantly issue from the nozzle U, the same as in an ordinary "blower." When the furnace-doors C C' are closed, the 90 heavy piston O turns the shafts F h in such a manner as to keep the roller i in contact with the door C', as more clearly seen in Fig. 3, said piston in this normal position of the attachment being at the bottom of the 95 cylinder P. Again, in this normal position of the attachment the air-inlets c c' are closed by the gravitating flaps D D'.

To charge the furnace, the door C' should

first be opened, during which operation the arm I swings around horizontally in the direction of the arrow seen in Fig. 3, thereby turning the shaft h in its bearings, and, by 5 means of the bevel-gears H G, imparting motion to the rock-shaft F. This rocking of said shaft coils the chains e e' K L around their respective disks E E' J, thereby opening the flaps D D', lowering the weight k, pulling 10 the piston O up to the top of cylinder P, and turning the roller M in the direction of the arrow seen in Fig. 2. Consequently the cam m' now opens the valve S and allows a full head of steam to flow through pipes T T', 15 nozzles U, and discharge directly into the furnace or fire-box. This discharge continues while the door C' remains open; but as soon as it is closed the heavy piston O again comes 20 into service and gradually restores all the operative parts to their normal positions, the speed with which said piston descends being regulated by the escape of air through the valve o. Said valve can be so set as to require from three to six minutes for the piston 25 to complete its descent, the time being determined by the size of the furnace and the special quality of the fuel consumed under the boiler. Finally, in some cases the devices G H h I i may be duplicated at the opposite side of the boiler, so as to enable the door C to operate the attachment and thus

render it unnecessary to pay especial attention to which door is first opened, as must be done when the parts are arranged as shown.

I claim as my invention—

1. The combination, in a smoke-consumer, of the furnace door C', provided with an air-inlet c', and gravitating flap D'; the chain e', connecting said flap with a disk E', secured to a rock-shaft F, having a bevel-wheel G 40 and disk J; the bevel wheel H attached to a shaft h, and gearing with the other wheel G; an arm I projecting from this shaft, and carrying a roller i, which bears against said door C'; a chain L, attached to said disk J, and 45 connected to a cataract-gear; a cam m', operated by said chain L; a valve S, opened by said cam; a steam-pipe T to which said valve is applied; and a series of nozzles projecting from said pipe, and discharging into the fur- 50 nace, for the purpose described.

2. In a smoke-consumer, of the class specified, the steam-pipe T, regulating-valve S, lever R, set-screw r', and cam m', for the purpose stated.

In testimony whereof I affix my signature in presence of two witnesses.

ROBERT H. MULLEN.

Witnesses:

JAMES H. LAYMAN,
A. W. MCCORMICK.
